UNITED STATES PATENT OFFICE.

FRANK WILCOMB, OF NORRISTOWN, PENNSYLVANIA.

SPlicing MECHANISM FOR KNITTING-MACHINES.

SPECIFICATION forming part of Letters Patent No. 691,686, dated January 21, 1902.

Application filed April 24, 1901. Serial No. 57,301. (No model.)

To all whom it may concern:

Be it known that I, FRANK WILCOMB, a citizen of the United States, residing at Norristown, Montgomery county, Pennsylvania, 5 have invented certain new and useful Improvements in Splicing Mechanism for Knitting-Machines, of which the following is a specification.

My invention relates to splicing attachments for knitting-machines and is an improvement upon that form of attachment disclosed by me in Letters Patent of the United States granted to me April 10, 1900, No. 647,849. In that attachment I provide means 10 whereby the rapidly-moving main thread was made to contact with the loose end of the splicing-thread to carry it into the fabric when the splicing is to be done. While in my present attachment I still use this action, I aim to 15 provide a structure and arrangement by which the loose end of the splicing-thread will never be shorter than a length determined upon as necessary to insure the splicing-thread being engaged and carried into the 20 fabric by the main thread when the latter is moved to contact therewith. In other words, I aim to have the splicing-thread when broken out of the fabric provided with a loose end which will reach from the clamp at least to 25 a predetermined point toward the needles which is sufficient to insure contact with the main thread when the latter is moved to engage and carry it to the needles.

As is well known, if yarn is subjected to a 30 direct pull between two points it is liable to break at any place intermediate of those points. I have found, however, that if the 35 yarn is held in contact with a curved surface and its free end is pulled upon it will not break at any point where it is supported by the said curved surface, but at some place between its last point of contact and the pulling-point. This principle has been utilized by me in the present improvement by providing 40 a curved or rounded surface over which the splicing-thread passes on its way to the needles, so that when the splicing-thread is clamped to be broken out of the fabric it will break at some place between the curved surface and the needles, which represent the pulling-point. By this means there will always 45 be left a predetermined length, at least, of

the splicing-thread between the clamp and the needles to afford sufficient contact with the main yarn to render certain the feeding in of 55 the splicing-thread. By my present arrangement a deflected or bent course is obtained for the yarn between the clamping-point and the needles, and when the main yarn is moved into contact with the splicing-yarn it is laid 60 along this bent or rounded course, and the tendency of the yarn to straighten out between the point of pull and the guiding-point insures a firm pressure of the main thread on the splicing-thread, with the result that the 65 splicing-thread will always be carried into the fabric at the time desired. In my present improvement I have sought to arrange the parts so as to facilitate threading, and for this purpose the clamping parts are located 70 at one side of the attachment, where they are readily accessible, and the course of the thread may be fully exposed by separating the clamping members.

In the accompanying drawings, Figure 1 is 75 a front view of the improved attachment. Fig. 2 is a side view showing it in relation to the cap-plate of the knitting-head to which it is secured and to the needles. Fig. 3 is a view similar to Fig. 2 with parts omitted and other 80 parts in section. Fig. 4 is a view similar to Fig. 3 with the parts in a different position from that of Fig. 3. Fig. 5 is a detail view of some of the parts in the position of Fig. 2. Fig. 6 is a plan view of Fig. 1. Fig. 7 is a detail view looking from the left of Fig. 1. Figs. 8 and 9 illustrate the principle upon which the invention is based. Fig. 10 is a view of a modification.

The attachment is secured to the knitting-head in any suitable manner, but preferably by a bracket *a*, secured to the cap *b* of the knitting-head. The bracket *a* has screwed thereto the thread-guide *c*, provided with the eye *d*, which directs the thread to the needles. This thread-guide and eye are substantially of ordinary form, and they are secured to the bracket independently of the attachment, as will be described hereinafter. Upon the bracket and to one side of the arm of the 90 thread-guide *c* a supplemental bracket *e* is screwed, and this has attached thereto a pair of guide-rods *f*, extending parallel with each other and held together at their outer ends 95 100

by a plate or link *g*, secured thereto by screws. Upon these rods a block *h* is adapted to slide freely, being operated by a link or rod *i*, Figs. 1, 5, and 6, from some part of the machine. 5 The operation of this rod and the block effects the throwing in or out of the splicing-thread, as will be described.

A sweep-arm or carrier *k* is pivoted to the lower part of the supplemental bracket, and 10 a slot *l* therein receives the elongated head *m* of a pin *n*, journaled in the block, so that as the block moves outwardly the sweep-arm will be swung downwardly from the position shown in Fig. 2 to that shown in Fig. 4, and 15 a reverse movement of the block will return the sweep-arm to the elevated position shown in Fig. 2. The sweep-arm carries guide-eyes 1 2 for the main and splicing threads, respectively. A movable guide and clamping arm 20 *o* for the splicing-thread is pivoted upon the same pin *p* which pivotally holds the sweep-arm. This clamping-arm is under tension of a spring *q*, which is coiled around the pin *p* and has its free end engaging a pin *r* on the 25 clamping-arm to press the same upwardly. The clamping-arm is provided with a guide-opening *s* for the splicing-thread and at its inner end with a curved V-shaped channel *t*, presenting a rounded path or surface adj- 30 cent to the main-yarn guide-eye *d* and over which the splicing-thread passes to be supported at all times thereon. The clamping-arm is moved downwardly to release the splicing-thread when splicing is to be done 35 by a cam-surface *u* on the block *h*, which engages the extension *v* of the pin *r*, carried by the clamping-arm, and forces the same downwardly when the block moves outwardly.

Immediately above the clamping-arm a 40 clamping-foot *w* is arranged in fixed position to coöperate with the movable clamping-arm to clamp and hold the splicing-thread when plain knitting is to be done. The upwardly-extending arm *x* of the clamping-foot is 45 screwed to the arm of the thread-guide *c*. This foot is slotted at *y* for the passage of the main thread. The course of the main thread is clearly shown in Figs. 2, 3, and 4. It passes first through the eye 5 of the guide-arm 6, 50 which is formed of an extension of the thread-guide *c*, thence through the eye 1 of the sweep arm or carrier, then through the slotted clamping-foot and the V-shaped groove or channel *t* in the clamping-arm, and finally 55 through the thread-eye *d* to the needles, as shown in Fig. 5. The splicing-thread passes from the guide-tube 8 laterally at an inclination to the guide-eye 2 of the sweep or carrier, and from this point it passes through the 60 channel *s* of the clamping-arm and thence between the clamping face or edge 10 of the clamping-arm and the clamping-foot, and from here it is deflected out of its straight course and extends downwardly over the 65 curved surface of the channel *t*, lying closely against the bottom of the V-shaped groove. From the groove the splicing-thread passes

through the thread guide or eye *d* to the needles, it lying just below the main yarn. Figs. 2 and 3 represent the positions of the parts 70 when only the main thread is passing to the fabric, the splicing-thread being broken and held by the clamping parts, with a stationary loose end supported on the curved surface or groove. It will be noticed that the loose end 75 of the splicing-thread extends over a curved surface between the clamping parts and the needles. This arrangement insures a loose end being left when the splicing-thread is broken out sufficiently long to be caught and 80 carried into the fabric when the main thread is moved so as to contact therewith.

The principle upon which this portion of my invention is based is illustrated in Figs. 8 and 9. If the yarn is subjected to a direct pull, as 85 indicated in Fig. 8, it is liable to break at any place between the point at which it is held (shown on the left of the figure) and the pulling-point, (represented by the fingers at the right,) and the rupture is just as liable to occur close 90 up to the clamping or holding point, as indicated at 11, Fig. 8, as at any other place, which would leave practically no loose end or one too short for the purpose. It is my object to render certain the breaking of the splicing-thread at a distance from the clamping-point, 95 said distance being never less than that determined upon as necessary to provide the length of loose end required, though it may be more. 100

Referring to Fig. 9, the yarn is represented as clamped by the finger upon a rounded or curved surface and extending from said clamping-point around said curved surface in contact therewith for some distance. By pulling upon the free end it will be found that the thread will not break at the points where it contacts with the curved surface, but at some point where it is free from said contact and support, (indicated, for instance, at 12, which, though close to the rounded surface, will leave a considerable length of loose end.) This is due to the fact that the frictional contact is sufficient to more than offset any inequalities in the strength of the yarn. 115

Figs. 3 and 4 represent how the invention is carried out practically. The splicing-thread passes, as before described, over the curved path or surface afforded by the bottom of the channel *t*, and when the clamp-arm is 120 operated to grasp the thread the pull at the needles will cause the breakage of the thread. The point of rupture will always be between the needles and the point at which the thread leaves the curved surface, so that at all times 125 a loose end of splicing-thread will be left which will be at least as long as is necessary to extend over the rounded surface. Generally the breaking-point of the splicing-yarn is at the top of the needle-cylinder or where 130 the stitch is made; but when using extremely fine yarn it frequently happens that owing to irregularities in strength the yarn will break at some other point, sometimes close to the

clamps, and at the next opening of the clamps the end becomes lost and no splicing can take place until again threaded by the operator. I overcome this irregular breaking as above described. When splicing is to be resumed, the block *h* is moved outwardly, thus causing the clamping-arm to be depressed by the cam-surface and the loose end of the splicing-thread released. At the same time the sweep-arm carrying the main thread is swung outwardly, and the rapidly-moving main thread is thus pressed down upon the splicing-thread firmly, and owing to the curved or bent course for the threads the contact will be stronger and more certain by reason of the natural tendency of the main yarn to straighten out between the eyes *1* and *d*. This contact of the main yarn against the splicing-yarn takes place first nearest the broken end of the splicing-yarn and then gradually increasing the contact-surface until sufficient grip on the splicing-yarn is secured to carry it to the needles, thus avoiding any liability of the broken end becoming doubled or looped, and thus tending to straighten the broken end, which will then go to the needles without becoming looped or bunched. The sweep-arm or carrier performs an additional function in that it provides slack in the splicing-thread at the time the splicing action is to take place and the loose end is to be caught and carried into the fabric by the main thread. At this time it is of course desirable that the loose end be as free from restraint or backward strain as possible, and this is effected by causing the sweep-arm to hold the splicing-thread, as shown in Figs. 2 and 3, normally out of a straight line drawn between the guide-tube and the clamp-arm, this position being assumed when knitting plain. When, however, the splicing-thread is to be thrown in, the outward movement of the sweep-arm to carry the main thread into contact with the loose end of the splicing-thread will at once provide a slack portion of the splicing-thread by freeing it from lateral pull, and this action takes place at the same time the clamp releases the splicing-thread.

Instead of pressing the clamping-arm upwardly by the spring, arranged as shown in Figs. 1 to 7, I may in some instances provide a spring-pressed plunger 13, Fig. 10, the upper end of which normally engages a notch or recess 17 in the lower edge of the clamping-arm *o'*. This plunger is carried by a barrel 14, pivoted to a bracket or post 15, secured to the knitting-head (represented generally at 16) in any desired manner. The plunger is pressed upwardly by a spring 17 in the barrel. By moving the barrel inwardly on its pivot, as shown in dotted lines in Fig. 10, the clamp-arm is free to swing downwardly on its pivot. The plunger will now engage with another notch 18 in the edge of the clamp-arm, and it will now be held in the position shown in dotted lines in Fig. 10. In this position of the clamp-arm the attachment can be readily

threaded. While this arrangement facilitates threading, it will be observed that threading may be easily done in the form shown in Figs. 1 to 7, the clamp-arm being simply pressed down against the pressure of its spring for this purpose. The parts have been arranged in both forms particularly with a view to render the operation of threading easy and rapid. In both forms the sliding block *h* is arranged at one side of the attachment and the clamping parts are left exposed at the other side and access may be had to the different parts of the course of the threads. By reason of the V shape of the pathway for the threads the main thread will be pressed firmly upon the splicing-thread, the inclined walls of the groove directing both the threads close together at the bottom of the groove.

I do not wish to restrict myself to the manner of bringing the main and splicing threads into and out of contact, as this may be done in other ways while still preserving the chief features of my invention.

I do not wish to limit myself to the arrangement of the curved or rounded surface for the splicing-thread on the clamping-arm. This performs a function independent of the clamping-arm; but I prefer to support this curved surface on the clamping-arm itself.

In order to provide for the knitting of slack stitches where the splicing-thread is thrown into work, a pivoted arm 23 is provided, similar to that shown in my former patent, pivoted to the bracket *e* and operated by a lug 26, carried by the block *h*, said arm 23 bearing upon the pin 25, which connects with the stitch-cam.

I claim as my invention—

1. In combination in a splicing device for knitting-machines, clamping means for the splicing-thread, a thread-bending surface between the same and the needles whereby the splicing-thread is bent on its way to the needles to be broken between said surface and the needles by the pull from the latter, and means for moving the main thread into and out of contact with the loose end of the splicing-thread lying on said surface, substantially as described.

2. In combination in a splicing device for knitting-machines, a main thread-eye for guiding both the splicing and main threads to the needles, clamping means for the splicing-thread, a thread-bending surface for the splicing-thread between the clamping means and the main thread-eye over which surface the splicing-thread is bent, and means for moving the main thread into contact with the splicing-thread, substantially as described.

3. In combination in a splicing device for knitting-machines, a main thread-eye for guiding both the splicing and main threads to the needles, clamping means for the splicing-thread, a curved bearing-surface for the splicing-thread between the clamping means and the main thread-eye over which surface the splicing-thread is bent, and means for

moving the main thread into contact with the splicing-thread, substantially as described.

4. In combination in a splicing device for knitting-machines, clamping means for the splicing-thread, a bearing-surface over which the splicing-thread is bent between the clamping means and the needles, and guiding means for the main thread, said main thread being also bent over said surface and 10 in contact with the splicing-thread when the latter is being fed to the needles, said guiding means being movable to move the main thread toward and from said surface, substantially as described.

15 5. In combination, clamping means for the splicing-thread, a thread-eye for guiding both the main and splicing threads to the needles, a supporting-surface between the clamping means and the thread-eye curving downwardly from the clamp and under the path of the splicing-thread extending to the said thread-eye said splicing-thread being bent or curved by contact with said surface, and resting with its loose end on said curved surface 20 25 when broken out of work, substantially as described.

6. In combination in splicing mechanism for knitting-machines, clamping means, means for providing a curved path for one of 30 the threads between the clamping means and the needles over which path the thread passes on its way to the needles and upon which the loose end of the splicing-thread rests and means for bringing the two threads together 35 on said curved path and for separating said threads leaving one on said curved path, substantially as described.

7. In combination in a splicing attachment for knitting-machines, a clamping-arm for 40 the splicing-thread having thereon between the clamping-point and the position of the needles a pathway for the said thread upon which it rests, and means for causing the main and splicing threads to engage each 45 other on said pathway, substantially as described.

8. In combination in splicing mechanism for knitting-machines, a movable clamping member for the splicing-thread having thereon 50 a pathway on which the splicing-thread rests between the clamping-point and the position of the needles whereby upon movement of the said member the way will be exposed for threading and means for bringing the 55 splicing and main threads together on said way and for separating them, substantially as described.

9. In combination in a splicing mechanism for knitting-machines, means for moving the 60 main yarn into contact with the splicing-yarn, said means being arranged on one side of the attachment and the clamp for the splicing-thread arranged on the other side of the attachment with the pathway for the thread 65 between the clamping-faces exposed laterally, substantially as described.

10. In combination in a splicing mechanism

for knitting-machines, the sliding block through the operation of which the threads are moved together or separated, a clamp for 70 the splicing-thread arranged laterally in respect to the said block, and means for operating the block, substantially as described.

11. In combination, the guide-eye for the threads, a vertically-movable clamping member 75 having a pathway thereon between the clamping-point and the guide-eye to direct the thread to the guide-eye and means for causing the main and splicing threads to engage and disengage on said pathway, substantially as described.

12. In combination, the guide-eye for the threads, a vertically-movable clamping member having a pathway upon which a loose end of the splicing-thread bears when broken and 85 means for moving the main thread to engage and disengage the splicing-thread, said pathway being located between the clamping-point and the guide-eye and the engagement and disengagement of the threads taking place on 90 said pathway, substantially as described.

13. In combination, the clamp, the bearing-surface between the clamping-point and the needles over which the splicing-thread passes on its way to the needles and means 95 moving over a curved path for laying the main thread on the splicing-thread held on said bearing, substantially as described.

14. In combination, the bearing-surface for the splicing-thread, means for holding the 100 said thread thereon with its end loose, and a sweep-arm pivotally supported for laying the main thread on said bearing-surface, substantially as described.

15. In combination, a clamp, the curved 105 bearing-surface for the splicing-thread between the clamping-point and the needles and the pivoted sweep for laying the main thread on the splicing-thread held on said surface with means for operating the sweep, substantially as described.

16. In combination, the bearing-surface for the splicing-thread, the pivoted sweep for the main thread to lay it on the splicing-thread, and a reciprocating block with operating 115 means therefor, said block being connected with the sweep, substantially as described.

17. In combination, the bearing-surface over which the splicing-thread passes, a reciprocating block and a sweep interposed between 120 said block and said bearing-surface and operated by the block, said sweep controlling the main thread, substantially as described.

18. In combination in a splicing attachment for knitting-machines, a vertically-movable 125 clamping member, a fixed clamping member above the movable member, the main guide-eye, the said clamping members being exposed at one side of the attachment with the course for the thread exposed laterally and 130 means for controlling the main thread, said fixed clamping member being slotted for the passage of the main thread, substantially as described.

19. In combination, the movable clamping member, the sweep-arm for the main thread, and a sliding block for operating said sweep-arm and clamping member, substantially as described. 35
20. In combination, the clamping means for the splicing-thread, a sweep-arm for controlling the main thread, said sweep-arm being adapted also to draw slack in the splicing-thread, substantially as described. 40
21. In combination, a bearing-surface for the splicing-thread for bending it from a straight line and means for bringing the main and splicing threads together and gradually increasing the length of contact between them on said surface, said contact being that of wrapping the main thread about said surface, substantially as described. 45
22. In combination, the reciprocating block, a clamping-arm arranged laterally thereof, an interposed sweep, operated from the block and the said clamp also being operated from the said block, substantially as described. 50
23. In combination, the clamping means for the splicing-thread, a spring for pressing the clamping parts together, means for automatically opening the clamping parts against the spring-pressure and means whereby the spring-pressure may be temporarily withdrawn so that the clamping parts may remain separated, substantially as described. 55
24. In combination in a splicing mechanism for knitting-machines, clamping means for
- the clamping members and adjustable spring-pressed means for holding the clamp either open or closed, substantially as described. 35
25. In combination in a splicing device for knitting-machines, a main thread-eye for guiding both the splicing and main threads to the needles, clamping means for the splicing-thread, a curved bearing-surface for the splicing-thread between the clamping means and the main thread-eye over which surface the splicing-thread is bent and upon which the loose end of the splicing-thread rests and means for bringing the main and splicing threads together on said surface and for separating them from each other, substantially as described. 40
26. In combination with the clamp for the splicing-thread, an adjustable spring-pressed plunger for holding the clamp either open or closed, substantially as described. 45
27. In combination with the pivoted clamp for the splicing-thread, a clamping-arm having the two notches and a swinging spring-pressed plunger for engaging either one or the other for holding the clamping-arm closed or open, substantially as described. 50

In testimony whereof I affix my signature in presence of two witnesses. 60

FRANK WILCOMB.
